UNITED STATES PATENT OFFICE

ERNEST DICKEY, OF DAYTON, OHIO, ASSIGNOR TO FRIGIDAIRE CORPORATION, OF DAYTON, OHIO, A CORPORATION OF DELAWARE

REFRIGERATING APPARATUS

Application filed March 25, 1929. Serial No. 349,798.

This invention relates to refrigerating apparatus. This application is a continuation in part of my co-pending application Serial No. 1,090, filed January 7, 1925, for refrigerating apparatus.

An object of this invention is to provide an apparatus or method for furnishing a refrigeration to a plurality of cabinets, or the like, in such a manner that the temperatures within the cabinets may be individually controlled. Thus it is possible to change either the temperature within the cabinet itself or within the freezing compartment with which the cooling units in the cabinets of this type are generally provided.

Further objects and advantages of the present invention will be apparent from the following description, reference being had to the accompanying drawings, wherein a preferred form of the invention is clearly shown.

In the drawings:

Fig. 1 is a view, somewhat diagrammatic, of an apparatus embodying features of this invention.

Fig. 2 is an elevation of a portion of the apparatus shown in Fig. 1.

Fig. 3 is a side view of an evaporator for use in this apparatus.

A refrigerating system embodying features of this invention may be provided with means to cause circulation of a cooling medium, such means being generally designated as 40. Such means may be capable of receiving evaporated refrigerant, liquefying said refrigerant and delivering the liquefied refrigerant, when a volatile refrigerant is used. Such means may be connected to a cooling medium circulation system, and, in the preferred form, such system may include a liquid refrigerant distributing line generally designated as 47 and an evaporated refrigerant collecting line generally designated as 45. The refrigerant collecting line 45 may be provided with two branches 29 and 36. These two branches may be maintained at different pressures by any suitable means. Preferably these different pressures may be obtained by providing an automatic pressure regulating valve 50 adapted to maintain a higher pressure in the branch 36 than in the branch 29.

This valve may be of the type disclosed in my prior application Serial No. 1,090. As disclosed in that application, such a system is capable of maintaining different temperatures in various evaporators. A soda fountain, 55

generally designated as 20, may be provided with two chambers to be cooled and designated as 26 and 32. The chamber 26 may be provided with an evaporator 25 and chamber 32 may be provided with an evaporator 31. 60

These evaporators may be of any suitable construction and preferably they are of the type disclosed in the co-pending application of Jesse G. King and Sylvester M. Schweller Serial No. 670,537, filed October 23, 1923, or 65

in the patent to Robert G. Osborn 1,556,708, patented October 13, 1925. Thus it will be seen that, because the branch 36 is at a different and higher pressure than the branch 29, the evaporator 25 is maintained at a cooler 70

temperature than the evaporator 31. The branches 29 and 36 may be continued to other parts of the building together with the line 47. Various evaporators may be connected with the distributing line 47, and may be connected either permanently or selectively with either of the collecting branches 29 or 36. Thus a water cooler 100 may have its evaporator connected with the distributing line 47 75

and with the collecting branch 36. Should the branch 36 be maintained at a pressure not quite suitable for water cooling temperatures a valve 50a may be interposed in the connection from the evaporator to the branch 36. 80

This valve 50a may be of the type disclosed in my application for refrigerating apparatus, Serial No. 349,796, executed concurrently herewith. It is obvious that if the branch 36 is maintained at too high a pressure for water cooling purposes or the like, 85

that the evaporator of the water cooler 100 might be connected to the branch 29 instead. The water cooler 100, preferably, though not necessarily, may be of the type disclosed in the co-pending application of John A. Macready Serial No. 296,239 filed July 30, 1928. 90

An ice cream cabinet 101 may be provided with an evaporator 102 of any suitable type, such as that heretofore referred to, and it may have its inlet connected by the pipe 103 95

100

with the distributing line 47 and its outlet may be connected by the pipe 104 with the collecting branch 29.

Cabinets 105 may be provided with evaporators 106 of the type heretofore referred to and more or less diagrammatically shown in Fig. 3. These evaporators may be provided with freezing trays 107 for freezing ice cubes in the well known manner. The inlets

10 of these evaporators may be connected by means of the pipes 108 with the liquid refrigerant distributing line 47. The outlets of these evaporators may be connected by means of the pipes 109 with the branch 36

15 and by means of the pipe 110 with the branch 29. Any suitable means such as a two way valve 111 may be provided for connecting or disconnecting the evaporators with either of the branches 29 or 36, and preferably the

20 valve may also be capable of disconnecting both of the evaporators in the manner indicated in Fig. 2. It is to be noted that in some systems it is desirable to provide a continuous downward gradient in the refrigerant

25 return line because of the lubricant return, and, when such is the case, the pipes 109 would be placed so that they would also be on the same level or in a lower position than the pipes 112. This can be accomplished by

30 considering the showing of the pipes 109 to 112 inclusive as a horizontal plan view rather than as a side elevation, so that the pipes 112, 109 and 110 are substantially in the same horizontal plane. If desired, the two way

35 valve may be provided with indicating means 114 and a pointer 115 for indicating the connection between the evaporator and the remainder of the system.

It is to be seen that the individual users of 40 the cabinets 105 may selectively connect the evaporators 106 with either of the branches 29 or 36 and thus they are able to secure different temperatures within the evaporators.

Means 40 may include an electrically driven 45 motor 41, a compressor 116, and the usual condenser, not shown, which may include a receiver 117 with which the line 47 may be connected. An automatic switch 80 may be connected by means of the pipe 85 with 50 the collecting line 45 in order to cause the means 40 to maintain the line 45 within predetermined pressure. The automatic means 80 may comprise an expansible bellows connected to the pipe 85 which actuates a snap switch which controls the starting and stopping of the motor 41 as more fully described 55 in my application Serial No. 1,090, heretofore referred to.

Thus it is seen that there has been provided 60 means for circulating a cooling medium to a plurality of cooling units, such means being connected with a cooling medium distributing line and with a cooling medium collecting line and in which one of the lines 65 is provided with two branches wherein the

cooling medium is maintained in a condition to impart selectively different temperatures to the cooling units within the cabinets to be cooled or the like.

While the form of embodiment of the invention as herein disclosed, constitutes a preferred form, it is to be understood that other forms might be adopted, all coming within the scope of the claims which follow.

What is claimed is as follows:

1. A refrigerating system comprising means for circulating a cooling medium, a plurality of cabinets, a plurality of cooling units in said cabinets, a cooling medium distributing line connected to said means and units, a cooling medium collecting line connected to said means and units, one of said lines comprising two branches wherein the cooling medium is maintained in a condition to impart different temperatures from said 80 branches respectively to said cooling units, and means to connect selectively either branch to any of said units and to disconnect the other branch.

2. A refrigerating system comprising 90 means for receiving evaporated refrigerant, liquefying said refrigerant and delivering said liquefied refrigerant, a plurality of cabinets, a plurality of evaporators in said cabinets, a liquid refrigerant distributing line 95 connected to said evaporators and to said means, an evaporated refrigerant collecting line connected to said evaporators and said means, one of said lines comprising two branches wherein the refrigerant is maintained in a condition to impart different temperatures from said branches respectively to said evaporators, and means to connect selectively either branch to any of said evaporators and to disconnect the other branch.

3. A refrigerating system comprising means for receiving evaporated refrigerant, liquefying said refrigerant and delivering said liquefied refrigerant, a plurality of cabinets, a plurality of evaporators in said cabinets, a liquid refrigerant distributing line connected to said evaporators and to said means, an evaporated refrigerant collecting line connected to said evaporators and said means, said refrigerant collecting line comprising two branches wherein the refrigerant is maintained in a condition to impart different temperatures from said branches respectively to said evaporators, and means to connect selectively either branch to any of 1 said evaporators and to disconnect the other branch.

4. A refrigerating system comprising means for receiving evaporated refrigerant, liquefying said refrigerant and delivering 1 said liquefied refrigerant, a plurality of cabinets, a plurality of evaporators in said cabinets, a liquid distributing line connected to said evaporators and to said means, an evaporated refrigerant collecting line connected to 1

5 said evaporators and said means, said refrigerant collecting line comprising two branches wherein the refrigerant is maintained in a condition to impart different temperatures from said branches respectively to said evaporators, and means to connect selectively either branch to any of said evaporators and to disconnect the other branch and means for maintaining said evaporators in a substantially 10 flooded condition.

10 5. A refrigerating system comprising means for receiving evaporated refrigerant, liquefying said refrigerant and delivering said liquefied refrigerant, a plurality of cabinets, a plurality of evaporators in said cabinets, a liquid refrigerant distributing line connected to said evaporators and to said means, an evaporated refrigerant collecting line connected to said evaporators and said 15 means, said refrigerant collecting line comprising two branches wherein the refrigerant is maintained in a condition to impart different temperatures from said branches respectively to said evaporators, and means to connect selectively either branch to any of said evaporators and to disconnect the other branch said last named means being capable of disconnecting both of said branches and 20 means for maintaining said evaporators in a substantially flooded condition.

20 6. A refrigerating system comprising means for receiving evaporated refrigerant, liquefying said refrigerant and delivering said liquefied refrigerant, a plurality of cabinets, a plurality of evaporators in said cabinets, a liquid refrigerant distributing line connected to said evaporators and to said means, an evaporated refrigerant collecting line connected to said evaporators and said means, one of said lines comprising two 25 branches wherein the refrigerant is maintained in a condition to impart different temperatures from said branches respectively to said evaporators, and means to connect selectively either branch to any of said evaporators and to disconnect the other branch, said last named means being capable of disconnecting both of said branches.

25 7. A refrigerating system comprising means for receiving evaporated refrigerant, liquefying said refrigerant and delivering said liquefied refrigerant, a plurality of cabinets, a plurality of evaporators in said cabinets, a liquid refrigerant distributing line connected to said evaporators and to said means, an evaporated refrigerant collecting line connected to said evaporators and said means, said refrigerant collecting line comprising two branches wherein the refrigerant 30 is maintained in a condition to impart different temperatures from said branches respectively to said evaporators, and means to connect selectively either branch to any of said evaporators and to disconnect the other branch, said last named means being capable of disconnecting both of said branches.

capable of disconnecting both of said branches.

8. A refrigerating system comprising means for receiving evaporated refrigerant, liquefying said refrigerant and delivering 70 said liquefied refrigerant, a plurality of cabinets a plurality of evaporators in said cabinets, a liquid refrigerant distributing line connected to said evaporators and to said means, an evaporated refrigerant collecting 75 line connected to said evaporators and said means, said refrigerant collecting line comprising two branches wherein the refrigerant is maintained in a condition to impart different temperatures from said branches respectively to said evaporators, and means to connect selectively either branch to any of said evaporators and to disconnect the other branch said last named means being capable of disconnecting both of said branches and 80 means for maintaining said evaporators in a substantially flooded condition.

9. A refrigerating system comprising means for receiving evaporated refrigerant, liquefying said refrigerant and delivering 90 said liquefied refrigerant, a plurality of cabinets, a plurality of evaporators in said cabinets, a liquid refrigerant distributing line connected to said evaporators and to said means, an evaporated refrigerant collecting 95 line connected to said evaporators and said means, said refrigerant collecting line comprising two branches wherein the refrigerant is maintained in a condition to impart different temperatures from said branch respectively to said evaporators, and means to connect selectively either branch to any of said evaporators and to disconnect the other branch, said last named means being capable of disconnecting both of said branches, and 100 float controlled inlet valves in said evaporators for maintaining said evaporators in a flooded condition.

10. A refrigerating system comprising means for circulating a cooling medium, a 110 plurality of cabinets, a plurality of cooling units in said cabinets, cooling medium distributing and collecting means connecting said means for circulating a cooling medium with said cooling units, said cooling medium 115 distributing and collecting means including a line comprising two branches wherein the cooling medium is maintained in a condition to impart different temperatures from said branches respectively to said cooling units, 120 and means to connect selectively either branch to any of said units and to disconnect the other branch.

In testimony whereof I hereto affix my signature.

ERNEST DICKEY.
